UNITED STATES PATENT OFFICE

165,554

COMBINED SEWING MACHINE CABINET AND CHAIR THEREFOR

Adolph Schukat, Chicago, Ill.

Application December 16, 1950, Serial No. 13,455

Term of patent 14 years

(Cl. D33—12)

To all whom it may concern:

Be it known that I, Adolph Schukat, a citizen of the United States, residing at Chicago, in the county of Cook and State of Illinois, have invented a new, original, and ornamental Design for a Combined Sewing Machine Cabinet and Chair Therefor, reference being had to the accompanying drawing, forming a part thereof.

Fig. 1 is a perspective view showing in closed position a combined sewing machine cabinet and chair therefor embodying the new design;

Fig. 2 is a perspective view showing the combined sewing machine cabinet and chair therefor with the chair separated from the cabinet and the drawers therein in open position; and

Fig. 3 is a perspective view on a slightly reduced scale of the chair of Fig. 2 showing the front and opposite side thereof.

The sides of the sewing machine cabinet not shown are similar to those shown, while the back of the cabinet and front of the chair portion are substantially plain.

I claim:

The ornamental design for a combined sewing machine cabinet and chair therefor, substantially as shown and described.

ADOLPH SCHUKAT.
